UNITED STATES PATENT OFFICE

2,425,156

INTERNAL-COMBUSTION ENGINE

Lloyd O. Knight, Clarendon, Pa.

Application March 12, 1943, Serial No. 478,931

8 Claims. (Cl. 123—55)

1

This invention relates to an internal combustion engine.

It is generally aimed to provide a more efficient and exceedingly compact engine of the dual cylinder type attaining greater uniformity in torque application and wherein the weight factor is small relative to horse power.

I especially aim to provide a means to cool the dual cylinders more efficiently than with forced air and more specifically to build or incorporate the intake manifold within the part or parts forming the crank case, preferably integral therewith, and provide distributing passages therefrom to the fuel inlets of the cylinders so that the supercharged fuel may be passed through said manifold and passages for vaporization and to further perform the function of cooling the engine. This feature of the invention provides a compact and short means of fueling and supercharging multiple dual cylinders, solves the problem of cooling such cylinders at the zones between the independent cylinders and also conceals the fuel supply and cooling system and renders it less vulnerable to damage as when employed in aircraft in combat.

In addition, an object is to provide a novel arrangement wherein the connecting rods are attached to a sleeve which is journaled on a crank or wrist pin of the crankshaft and which rods are spaced along the sleeve from or disaligned with anti-friction bearing devices at the ends of the sleeve so as to absorb the dangerous part of the shock of explosions in combination with a novel lubricating system which maintains a body of lubricant between the sleeve and pin to afford a cushion.

Other objects are to provide a novel direct system for the lubrication of the moving parts and a timing system wherein valves for different cylinders may be operated from a single cam.

The more specific objects and advantages will become apparent from a consideration of the description following taken in connection with accompanying drawings illustrating one operative embodiment.

In said drawings:

Fig. 1 is a view of the engine primarily in vertical section perpendicular to the crank shaft;

Fig. 2 is a view primarily in vertical section taken at a right angle to Fig. 1;

Fig. 3 is a cross-sectional view through one of the banks of cylinders;

Fig. 4 is a view in elevation looking toward the inner face of one of the crank case sections, particularly showing the intake manifold part formed integral therewith;

2

Fig. 5 is an enlarged vertical sectional detail on approximately the same plane as Fig. 2 to show the crank and connecting rod assembly and means of lubrication, and

5 Fig. 6 is a central longitudinal section through a modified form of bank of cylinders.

Referring specifically to the drawings wherein like reference characters designate like or corresponding parts, 10 designates a crank case from which radiate banks 11 each having a pair of integral dual cylinders 12. Such parts are adapted to be mounted so as to remain stationary in operation.

Said crank case 10 is made in separable sections, preferably two, as at C and D. These sections are disposed end to end longitudinally with respect to a crank shaft 13. Each section has an outer end wall 14 in which said crank shaft is journaled centrally and directly preferably in 15 anti-friction bearing devices 15 of the type having concentric race members 16 and interposed rolling elements such as balls, cylinders or the equivalent 17. To one end wall 14, a cap plate 18 is bolted at 19 while from the other end wall 14, a marginal flange 20 projects and has a supplemental case section 21 bolted to it at 22.

Each crank case section C and D has an annular inwardly extending wall 23 integral with its end wall 14 and at the junction of annular walls 23 20 they have opposed inwardly extending rims or flanges 24 separably bolted together as at 25.

It is to be particularly noted that said rims 24 have registering annular depressions or channels 26 whereby an intake manifold for supercharged 30 fuel is provided and which may be gasoline or other hydrocarbon supplied in the conventional manner from a carburetor and supercharger (not shown) fastened in communication with an inlet 27.

40 Reverting to the banks 11, they have flat bases bridging the junction of the crank case sections C and D and flanges 28 whereby they are bolted at 29 to flat seats 30 on the periphery of annular walls 23 with the bores or interiors of cylinders 45 12 registering with openings 31 in said walls 23.

Bolted at 32 to each bank 11 is a cylinder head 33 common to both cylinders 12 of that bank. The interior or space within each cylinder head is divided by partitions 34 providing fuel inlet passages 35 having central inlets 35^a and exhaust 50 passages 36 respectively communicating with the firing chambers of the cylinders under control of conventional inlet valves 37 and exhaust valves 38.

55 In each cylinder bank 11 a fuel passageway 39 is provided longitudinally between each cylinder 12

of the bank with its inner and outer ends, respectively, in communication with manifold 26 and passage 35, the latter as shown being common to both cylinders of the bank. Thus the supercharged fuel will be supplied from the manifold 26 through passages 39 and 35 to the cylinders, exhausting after firing through passages 36 directly into the atmosphere or through a manifold (not shown) as desired. The walls of the cylinders are preferably reinforced by thickening them at 40 within passages 39 adjacent each end of the latter.

The particular construction and arrangement of the intake manifold 26 and associated passages provides a compact and short means for fueling and supercharging multiple cylinder engines. By it, I attain maximum efficiency in vaporizing the fuel through heat exchange as well as in the cooling of the cylinders by the fuel especially at the zones between them. The said manifold and passages are obscured and concealed so as to be less accessible and vulnerable to damage in case of combat, especially when employed in aircraft.

The explosions from the supercharged fuel within the firing chambers of the cylinders 12 are timed and effected by conventional ignition means in coaction with the valves 37 and 38 to drive reciprocating pistons 41 within the cylinders. A pair of connecting rods 42 and a plurality of connecting rods 43 are journaled on hollow wrist pins 44 carried by said pistons. Said connecting rods 42 operate within the dual cylinders of one bank 11 and are bolted at 45 against flat surfaces 46 of a crank sleeve 47 while the connecting rods 43 are pivoted on journal pins 48 each mounted in pairs of lugs 48^a on said crank sleeve 47. Bushings 48^b are interposed between the pins 48 and coacting connecting rods.

The aforesaid crank shaft 13 has webs 50 mounting a crank in the form of a pin 51 on which said crank sleeve 47 is journaled. Counter-balancing weights 152 may be carried by the webs 50.

Crank 51 has reduced ends 52 removably fitted in openings of the webs 50 and held in position by means of screws 53 threaded into the bore 54 of the latter and having heads 55 overlapping the webs. On reduced portions 52 and engaged in recesses 56 of crank sleeve 47, are anti-friction bearing devices 57 like those at 15. The periphery of crank pin 51, between such devices 57, is of less diameter than and spaced from the bore wall of the sleeve to provide a lubricant reservoir 58 at the ends of which the metal-backed felt or other porous washers 59 are disposed to permit escape of lubricant in a quantity sufficiently restricted to lubricate only the bearing devices 57 and adjacent parts. The thrust of the crank sleeve 47 is against anti-friction bearing devices 59^a of the type like those at 15 and 57, which are positioned in recesses 60 of the webs 50 between such webs and ends of said crank sleeve and contacted by said bearing devices 57.

Particular attention is called to the fact that the connecting rods 42 and 43 are not directly over the zones of bearing contact of the crank sleeve 47 with crank or pin 51 but rather are inwardly thereof spaced from the planes of the ends of such sleeve, and accordingly with the sleeve made of the proper metal and of correct size according to the explosive pressures from the pistons 41, said crank sleeve 47 will take the dangerous parts of the shocks from the explosions away from the bearings. Also the body and pres-

sure of oil or lubricant in reservoir 58 will serve to reduce or absorb the aforesaid shocks.

The crank case utilizes the dry sump system of lubrication, a suction pump taking the oil out of the crank case as it drains from the pressure system but in order to directly lubricate the various working parts not reached thereby, the crank shaft 13 has a channel or passage 61 to which lubricant is supplied continuously under pressure as from a conventional pump (not shown) through a fitting 61^a and from which it spreads through a branch 61^b to a passage 62 in pin 51, thence through passages 63 in one of the screws 53 into a passage 64 of said pin 51 to reservoir 58. From the latter the lubricant spreads through passages 65 in the crank sleeve 47, passages 66 in the connecting rods 42 to the periphery of wrist pins 44 thereof, and also spreads through passages 67 in said crank sleeve, passages 68 in certain of the lugs 48^a, into passages 71 of connecting rods 43 to the periphery of the adjacent wrist pins 44. Screws 72 are threaded into certain lugs 48^a and the pins 48 to fasten the latter in place and plug the extremities of passages 69 caused in drilling. Screws 73 plug other extremities of said passages 69 caused in the drilling thereof.

By way of example, I have disclosed the engine as having five banks of cylinders and pistons. It is to be understood, however, that the number may be varied and for instances, be three, seven, nine, etc. still carrying out the same principles.

Cam shafts 74 are used to operate the valves 37 and 38, being driven from a chain of gears 74^a from crank shaft 13; the specific operating means 35 between the valves and shafts being conventional and not shown. The structure, however, enables me to use two cam shafts for three banks or six cylinders and only one cam shaft added for every two banks or four cylinders added.

Conventional heat-dissipating fins 74^b may be provided on the cylinders 12 and fins 76 may be formed on such cylinders and extend into the passages 39 as shown in the modification of Fig. 6, to promote the heat-exchanging effect between the relatively cold fuel therein and the heat produced in operating the engine.

Various changes may be resorted to provided they fall within the spirit and scope of the invention.

I claim as my invention:

1. An internal combustion engine having a crank case, cylinders associated therewith, a shaft having a crank operable in said crank case, pistons operable in said cylinders, said crank case comprising separable sections each having an end wall and a channel spaced therefrom, said channels registering and facing each other and collectively forming an intake manifold for the supply of fuel to operate said pistons.

2. An internal combustion engine having a crank case, cylinders associated therewith, a shaft having a crank operable in said crank case, pistons operable in said cylinders, said crank case comprising sections having end walls and cylindrical walls disposed end to end and in abutment, said sections at their abutting ends having integral depressed portions registering with each other and collectively forming an intake manifold spaced from said end walls for the supply of fuel to operate said pistons.

3. An internal combustion engine according to claim 2 wherein said abutting sides are walls having coacting securing flanges at the inner margins, and wherein the manifold has outlets at the periphery of the crank case.

4. A crank case having separable sections provided with end walls and cylindrical walls extending therefrom, said cylindrical walls remote to said end walls being fastened in abutting relation, one of said sections at the zone of abutment having an endless depression in its wall coacting with the opposed wall to provide an intake manifold.

5. A crank case having separable sections arranged side by side and having end walls and inwardly extending rims at the zone of contact, one of said rims having an endless depression coacting with the opposed rim in spaced relation to the end walls to provide an intake manifold, and one of said sections having discharge outlets at 10 the periphery of the crank case.

6. An internal combustion engine according to claim 1 wherein the cylinders are in banks and fuel passages are provided in the banks between the cylinders thereof in communication with the manifold.

7. An internal combustion engine according to claim 1 wherein the cylinders are in banks having a plurality of them integral with each other, each bank having a fuel passage between the cylinders thereof in communication with the manifold.

8. An internal combustion engine according to

5 claim 1 wherein the cylinders are in banks having a plurality of them integral with each other, each bank having a fuel passage between the cylinders thereof in communication with the manifold, cylinder heads on the banks, and said heads having fuel passages communicating with the first mentioned fuel passages, the second mentioned fuel passages being common to all cylinders of the associated bank.
